BATH CUSHION

Bavven de Grandcourt, Norwalk, Conn.

Application July 15, 1931, Serial No. 550,881

3 Claims. (Cl. 4—185)

The present invention has for an object to provide an improved sanitary bath cushion conveniently attachable to a bath tub to serve as a head rest when taking therapeutic baths the value 5 of which depends largely upon the degree of relaxation attained.

The invention provides a cushion designed to provide a perfectly comfortable rest for the head and neck to facilitate complete physical relaxation in the regulated temperature baths so frequently recommended in various therapeutic treatments. The cushion in its preferred form provides an upper resilient head pad portion and lower resilient neck pad portion adapted to press 15 gently against the muscular portion of the back of the neck to provide a gentle pressure and a suitable support. By this arrangement complete comfort is provided making possible physical relaxation and release of all nervous tension. At 20 the same time the head is protected from contact with the hard surface of the tub and the neck and shoulders are supported in a relaxed position most suitable for complete comfort in the bath.

The nature and objects of the invention will 25 be better understood from a description of a particular illustrative embodiment thereof and for the purpose of which description reference should be had to the accompanying drawing forming a part hereof and in which—

Fig. 1 is a perspective view showing the cushion in place in a bath tub,

Fig. 2 is a top plan view showing in outline the retaining cups,

Fig. 3 is a bottom plan view of the preferred 35 form of cushion,

Fig. 4 is a sectional view on the line 4—4 of Fig. 2, and

Fig. 5 is a sectional view on the line 5—5 of Fig. 2.

The cushion shown for the purposes of illustration in Figs. 1 to 4 consists of a unitary sponge rubber pad 5 forming a resilient cushion of generally semi-circular shape having an upper relatively thin head rest portion 6 and a lower thicker neck rest portion 7 adapted to press resiliently against the back of the neck to provide a gentle resilient pressure and support, together with a suitable enclosing sheath 8.

In the particular embodiment shown, the cushion as a whole is of a general semi-circular shape to provide substantial width whereby it may rest securely in position against the end of the tub. The cushion is preferably slightly curved in a transverse direction as indicated in Fig. 1, in order that it may the better fit the lateral curva-

ture of the end of the usual bath tub. By so forming the cushion the wrinkling of the front surface which would occur if a flat cushion were bent against the curved tub end is prevented.

If the sponge rubber pad is formed in a mold, 60 the sheath may constitute the surface skin of the rubber which skin is formed against the mold in the process of vulcanizing the sponge rubber. If, however, the cushion is otherwise formed, the sheath may be, as shown in Fig. 2, a separate 65 casing 8 of suitable impervious material such, for example, as rubber or rubberized silk, which may be packed or padded with any suitable cushioning and preferably waterproof padding material such as sponge rubber. Preferably instead 70 of making this sheath removable it is sealed so that it is completely air and water tight. If desired, although this is ordinarily not necessary, the sheath may be cemented to the sponge rubber pad throughout its entire area. 75

The lower edge of the cushion is shown as slightly curved, as indicated at 8, but the cushion is so located in the tub 9 that the outer edges of the cushion do not extend downward far enough to project beneath the shoulders of the 80 user when the head is positioned against the upper pad portion and the neck is resting against the neck pad. In this way the shoulders may rest against the tub while the neck and head only are supported by the cushion, which gives a more 85 relaxed and natural position than would be possible if the lower part of the pad formed a ridge under the shoulders or other part of the body.

Suitable attaching devices may be applied to 90 secure the cushion in position against the end of the bath tub. As shown, vacuum cups 10 are provided in position to engage the tub somewhat below the upper edge of the cushion. Any suitable number of vacuum cups may be provided as desired, or hooks projecting over the edge of the 95 tub may be used. Vacuum cups are preferred because of the greater ease with which the cushion may be adjusted in the tub to the height of various persons who may use the cushion. Four such vacuum cups 10 are shown and it is to be 100 noted that these vacuum cups are spaced a sufficient distance from the upper edge of the cushion, so that the head pad portion may extend above the upper edge of the tub, thereby to permit the head to rest on the cushion as the cushion 105 overlies the top of the tub. An even number of vacuum cups is preferred so that the head will rest between two cups rather than on one cup. The vacuum cups 10 are preferably located as indicated in Fig. 3 with two cups nearer the lower 110

outside edges of the cushion to hold it in firm position.

It will be understood that the foregoing particular description is illustrative of a preferred embodiment of my invention and is not intended as defining the limits of the invention.

I claim:—

1. A bath cushion of the character described consisting of a unitary sponge rubber pad of generally semi-circular shape presenting an upper relatively thin head rest portion and a lower thicker neck rest portion, and an impervious sheath completely enclosing said sponge rubber pad, together with a plurality of suction cups affixed to the back of said sheath at points spaced from the upper edge for securing the cushion in a bath tub in position to permit the upper portion to project above the upper edge of the tub.
2. A bath cushion of the character described consisting of a sponge rubber cushioning pad of generally semi-circular shape and curved laterally on its posterior face to conform transversely to the curve of the tub, said cushion presenting an upper relatively thin head rest portion and a lower thicker roll shaped neck rest portion, said neck rest portions being short vertically to avoid

extending down beneath the shoulders, and an impervious sheath completely enclosing said pad, together with a plurality of suction cups affixed to the back of said sheath at points spaced downwardly from its upper edge for securing the cushion in a bath tub in position permitting its upper edge to extend above the upper edge of the bath tub.

3. A bath cushion of the character described consisting of a sponge rubber cushioning pad of generally semi-circular shape and curved laterally on its posterior face to conform transversely to the curve of the tub, said cushion presenting an upper relatively thin head rest portion, and a lower thicker roll shaped neck rest portion, said neck rest portion being short vertically to avoid extending down beneath the shoulders, and an impervious sheath of rubberized silk completely enclosing and cemented to the sponge rubber pad, together with a plurality of suction cups affixed to the back of said sheath at points spaced downwardly from its upper edge for securing the cushion in a bath tub in position permitting its upper edge to extend above the upper edge of the bath tub.
